CLAIM

The ornamental design for a RANGE, as shown and described.

DESCRIPTION

FIG. 1 is a perspective view of a RANGE showing the new design, according to a first embodiment;

FIG. 2 is a top view thereof;

FIG. 3 is a bottom view thereof;

FIG. 4 is a front view thereof;

FIG. 5 is a rear view thereof;

FIG. 6 is a right side view thereof;

FIG. 7 is a left side view thereof;

FIG. 8 is a perspective view of a RANGE showing the new design, according to a second embodiment;

FIG. 9 is a top view thereof;

FIG. 10 is a bottom view thereof;

FIG. 11 is a front view thereof;

FIG. 12 is a rear view thereof;

FIG. 13 is a right side view thereof; and

FIG. 14 is a left side view thereof.

The broken lines shown are included for the purpose of illustrating environment or unclaimed portions of the article and form no part of the claimed design. The shading lines shown in the drawings represent the approximate three-dimensional contour of the design, and are not intended to indicate surface decoration.
